[57] CLAIM

The ornamental design for the portable cooler and housing therefor for a vehicle, as shown and described.

DESCRIPTION

FIG. 1 is a top, front, left side perspective view of the portable cooler and housing therefor for a vehicle showing my new design;

FIG. 2 is a top, front, left side perspective view thereof;

FIG. 3 is an exploded perspective view thereof;

FIG. 4 is a front elevational view of the cooler portion;

FIG. 5 is a front elevational view of the housing portion;

FIG. 6 is a side elevational view thereof in an open position;

FIG. 7 is a rear elevational view housing portion; and,

FIG. 8 is a rear elevational view of the cooler portion. The cooler and housing are shown separately in FIGS. 4-8 for clarity of illustration.
